UNITED STATES PATENT OFFICE

2,223,679

MEANS FOR SEPARATING PARTICLES OF
SOLID MATERIAL BY FLOTATION

Russell Scott Ellis, Vineland, N. J.

Application April 19, 1939, Serial No. 268,668

6 Claims. (Cl. 209—211)

My present invention relates to methods and means of the same general character as disclosed in Letters Patent of the United States No. 2,104,537 granted to me January 4, 1938, and No. 5 2,146,672 granted to me February 7, 1939, and is applicable to any material particles of different sizes or specific gravity, or both, for instance, natural sands, comminuted stone, coal, vegetable grains, or any other substances, by the application 10 thereto of water or other fluid or mixture of fluids under pressure to effect flotation thereof, and consequent separation of such particles.

The apparatus disclosed in said patents includes a plurality of separator casings, utilized 15 as distinct receptacles for the material to be treated, disposed in a vertical series; and connected in series relation by conduits through which solid material which is not precipitated in the lowermost receptacle is delivered into the 20 next higher receptacle, and the material which is not precipitated in the second receptacle is delivered into a third receptacle, and so on, the materials precipitated in the several receptacles being discharged separately from the bottoms 25 thereof, and the finest materials, finally separated by flotation, being discharged from the top receptacle.

In the form of my invention chosen for illustration herein, as in each of said patents, the 30 separator casing has a conical portion with its apex extending vertically downward, and has an inlet conduit for the material to be separated extending tangentially into one side thereof below the top, and an outlet conduit extending tangentially from the upper part of the casing. An axial inlet conduit for the flotation fluid extends vertically through said casing in coaxial relation therewith. That conduit is connected with two distinct flotation fluid supply conduits, respectively 35 above and below said casing, through either or both of which flotation fluid may be delivered into the casing under pressure and including means for varying the effective area of the orifice through which the flotation fluid is discharged 40 into the casing. An outlet is provided extending laterally at the lower end of the casing through which the material precipitated in the casing is discharged.

Each of said patents discloses axially opposed 50 spreader jet plates, inclosed by and in coaxial relation with the separator casing, affording an annular orifice through which the flotation fluid is distributed into the casing. My present invention not only provides improved means for 55 effective relative axial adjustment of said spread-

er plates to vary the effective area of the annular orifice between them, but also improved valve means for controlling the passage of flotation fluid downward from within the spreader plate structure to facilitate the discharge of the 5 precipitated material which gravitates downward outside of said spreader plate structure, within and from the separator casing. As hereinafter described, such valve means includes a circular plate having a circular series of openings therethrough adapted to register with or more or less obstruct a similar circular series of openings in a stationary diaphragm in said spreader structure; said valve plate having a tubular extension forming a sleeve closely fitting around said axial inlet conduit for the flotation fluid and having a radially projecting handle by which said sleeve and plate may be turned.

My invention includes the various novel features of construction and arrangement and 20 method of operation hereinafter more definitely specified.

In said drawings, Fig. I is a diagrammatic elevation including a single separator casing conveniently embodying my improvements.

Fig. II is a vertical sectional view of the lower portion of the structure shown in Fig. I, but on a larger scale.

Fig. III is a plan sectional view, taken on the line III, III in Fig. II.

Fig. IV. is a plan view of the perforated diaphragm in the spreader structure shown in Fig. II.

Referring to Fig. I, 1 is a conical separator casing having its apex downward, and the inlet conduit 2 for the material to be separated extending tangentially into the side thereof. The axial inlet conduit 3 for the flotation fluid extends vertically through the casing 1, in coaxial relation therewith, and has vents 3a in said casing. Supply conduits 3b and 3c connect said conduit 3 with means for delivering flotation fluid through it into said casing 1, under pressure, for instance a pump 5. The supply of flotation fluid through conduits 3b and 3c may be controlled by respective valves 4 and 4a. Natural sand is supplied through conduit 2, mixed with flotation water and under pressure, from pump 6.

I find that the maximum speed of separation 50 of sand is attained by predetermining an upwardly extending path in the separator casing from the inlet 2 to the upper tangential outlet 7, for the lighter material, which may extend to the next in a series of such separator casings, 55

as indicated at 1, at levels successively higher than the initial separator casing.

Therefore, I provide baffle means between said inlet and outlet, to form such a path in said casing 1, between said material inlet 2 and said upper outlet 7. As described in said Patent 2,146,672, such baffle means includes a sector of a cylinder 8 in coaxial, and laterally inwardly spaced, relation with the perimeter of said casing 1, and having at its lower end the sector of an annular plate 8^a which extends in a substantially horizontal plane at its upper portion, but has the downward extension 8^b at one end, pendent over said material inlet 2; whereby the lighter material is skimmed from the material being precipitated, and its upward passage from beneath said partition plate 8^a to said outlet 7 is facilitated.

The cylindrical receptacle 9 for flotation fluid, surrounds said inlet conduit 3 in coaxial relation therewith and has the plane diaphragm 9^a with a circular series of openings 9^b therethrough through which a predetermined limited quantity of the flotation fluid may be permitted 25 to escape into the cylindrical lower portion 1^a of the separator casing through which the material precipitated in said casing is discharged by way of the outlet 10. The effect of that arrangement is that the precipitated material is 30 turbulated in and by the flotation fluid passing downwardly through said diaphragm 9^a, and its progress to and through said discharge outlet 10 thus facilitated. However, the upper end of said receptacle 9 has the outwardly flared completely 35 annular spreader flange 9^c over which the major portion of the flotation fluid is distributed uniformly into the annular space 1' in said casing 1. The diaphragm plate 9^d, which is tightly fitted at the top of said receptacle 9 around 40 said axial conduit 3, rigidly supports said flange 9^c in coaxial relation with said axial conduit, but is provided with a circular series of ports 9^e which permit the flotation fluid to pass freely therethrough.

It is to be particularly noted that, as shown in Fig. II, said annular space 1' is of uniform width from the bottom to the top thereof, but but is of gradually increasing diameter and correspondingly increasing area from the bottom 50 to the top thereof, so that the rate of upward motion of the flotation fluid from the bottom to the top of said space gradually diminishes, and its rate of movement at the top of the annular spreader flange 9^c is approximately one-half of 55 the rate of its movement in the zone surrounding said diaphragm plate 9^d. Consequently, the lighter solid material being conveyed upward in said annular space 1', by the flotation fluid, is separated and escapes more rapidly from the 60 other solid material than if the rate of upward movement thereof at the top of said flange 9^c were as great as at the lower end of said flange, and its change of movement, from vertical to vertical direction in the upwardly increasing 65 greater area above the top of said flange 9^c is facilitated and the heavier particles of solid material are free to gravitate back down the conical wall of said casing 1 in said space 1' at an accelerated rate corresponding with the 70 downwardly diminishing area of said space 1'.

I find it convenient to provide said diaphragm 9^a in said receptacle 9 with the pendent cylindrical sleeve 9^f closely fitting said axial conduit 3 to further rigidly support said spreader structure in coaxial relation with said conduit 3.

As means to adjustably vary the effective area of said openings 9^b, I provide the circular valve plate 11 with a circular series of openings 11^a therethrough adapted to register with, or more or less obstruct, the circular series of openings 9^b in said stationary diaphragm 9^a. Said valve plate 11 has the tubular extension forming a sleeve 11^b closely fitting the outer cylindrical surface of said sleeve 9^f, and having the radially projecting handle 11^c by which said sleeve 11^b and valve plate 11 may be turned. I find it convenient to provide said handle 11^c with the index pointer 11^d adapted to traverse the arcuate scale plate 1^b which is mounted on the outer cylindrical surface of the casing cylinder 1^a. Said scale plate 1^b may be provided with a series of circumferentially spaced graduations to manifest the position of said valve and indicate the effective area of the openings 9^b in the diaphragm 9^a determined by adjustment of said valve plate 11 by the handle 11^c.

To prevent accidental rotary displacement of said spreader structure 9 by rotary adjustment of said valve plate 11, I provide said cylindrical receptacle 9 with the inwardly projecting bracket 9^g which has a hole extending therethrough parallel with the axis of said conduit 3 to receive the upper smooth cylindrical end of the stop bolt 9^h which may be secured in adjusted position by the nut 9ⁱ.

A second cylindrical receptacle 12 for flotation fluid, having a completely annular spreader flange 12^a at the lower edge thereof, is axially opposed to said flange 9^c above the latter and is fixed on said axial conduit 3, by any convenient means. The diaphragm plate 12^b, which is tightly fitted around the axial conduit 3 at the junction of said receptacle 12 with the flange 12^a, rigidly supports said flange 12^a in coaxial relation with said axial conduit, but is provided with a circular series of ports 12^c which permit the flotation fluid to pass freely therethrough.

The spreader structure including said flange 9^c is axially adjustable on said axial inlet conduit 3, so that the operator may precisely determine and vary the area of the completely annular fluid passageway between said flange 9^c and the flange 12^a. For that purpose, the pendent cylindrical sleeve 9^f, which is slip-fitted on said axial conduit 3, has rigidly, but detachably, 50 connected therewith the packing collar 13 by which the receptacle 9 and spreader flange 9^c may be manually raised and lowered, through the stuffing box 14 on the bottom of said casing member 1^a.

Said collar 13 contains two packing rings; first, the ring 13^a, preferably formed of ductile metal such as tin, lead, or copper, adjustable by the screw gland 13^b to normally rigidly connect said collar and the sleeve 9^f, and, second, 60 the flexible ring 13^c which is formed of lubricated cotton and adjustable by the screw gland 13^d to prevent fluid leakage from the interstice between said axial conduit 3 and sleeve 9^f.

The packing collar 15 contains but one packing ring 15^a, preferably formed of ductile metal and adjustable by the screw gland 15^b to normally rigidly connect said collar with said axial inlet conduit 3 in any desired position of vertical adjustment determining the effective area of 70 the annular fluid passageway between said spreader flange 9^c and 12^a. I find it convenient to provide said collar 15 with the annular flange 15^c fitted to overlap the packing collar 13 so that said collar 15 may be clamped upon the conduit 75

3 to lock the collar 13 and the spreader flange 9^c connected therewith in any position to which it may be adjusted by the operator.

- Moreover, I find it convenient to provide said 5 casing 1 and each of the other casings in the series with respective stuffing boxes 16 at the top thereof through which said axial conduit 3 is axially adjustable, so that the operator may place the upper spreader flange 12^a in any desired 10 position with respect to the height of said casing 1, said casing 1 and the inlet conduit 3 being rigidly connected in any position of relative adjustment by pressing the packing in said stuffing box 16.
- 15 The precipitated material discharge outlet conduit 10 of casing 1, and each casing in the series employed, may be supplemented to convey the precipitated material from each separator casing into respective bins. I prefer to provide 20 each such outlet 10 with means for adjustably predetermining the effective area thereof and, for that purpose, provide the valve casing 18 with a slot 18^a opening through one side thereof to receive any selected one of a series of slide 25 plates 18^b having respective discharge openings 18^c therethrough of respectively different sizes. The upper discharge outlet 1 from the uppermost separator casing in the series, may likewise be supplemented with a conduit leading to a bin 30 for the overflow material discharged therethrough.

It is to be understood that the solid material delivered into the separator casing 1 through the inlet conduit 2, mixed with flotation water 35 and under pressure from pump 6, tends to gravitate toward the bottom of said casing, and the pressure of the flotation fluid supplied to said casing determines what portion of the solid material is permitted to be precipitated in said 40 casing past the annular jet of flotation fluid, for instance, clear water, passing radially outward through the annular opening between said spreader flanges 9^c and 12^a. The solid material tending to pass downward between the flange 9^c 45 and the casing 1 through the annular space 1', is turbulated by the flotation fluid which finds its main outlet at the top of the casing through the upper tangential conduit 1, carrying with it the lighter material which has not been permitted 50 to precipitate to the bottom of the casing but which may be precipitated in a similar casing higher in the series.

However, I do not desire to limit myself to the precise details of construction, arrangement, or 55 method of operation herein set forth, as it is obvious that various modifications may be made therein without departing from the essential features of my invention, as defined in the appended claims.

60 I claim:

1. In means for separating particles of solid material by flotation; the combination with a separator casing, which is conical, with its apex downward, and has a lateral inlet for the material to be separated, a lateral outlet for the material precipitated in said casing, and a lateral outlet for the material not precipitated in said casing; of a conduit for flotation fluid extending axially in, and having lateral vents within, said 65 casing; a circular receptacle for said fluid, surrounding said vents, in coaxial relation with said casing and conduit, and in radially spaced relation with said casing; a flange at the top of said receptacle which is conical with its apex downward and in substantially equally spaced 70

relation with the inner wall of said casing from the bottom to the top of said flange; whereby, upward movement of the flotation fluid in the space between said casing and flange is decelerated from the bottom to the top of said flange 5 and the lighter particles of solid material thereby freed for separation and discharged through said lateral outlet; a diaphragm within, and in integral relation with the lower part of said receptacle, and having a series of fluid outlet ports 10 therethrough, leading to the region in which material is precipitated, and a cylindrical sleeve slidably fitted around said conduit; a circular valve plate, fitted to said diaphragm, and having ports adapted to register with the dia- 15 phragm ports, and a cylindrical sleeve slidably fitted around the receptacle sleeve and extending exterior to said casing; a handle on said sleeve, whereby it may be turned to adjustably, variably, determine the effective area of said 20 ports, and thereby predetermine the relative volumes of flotation fluid respectively directed upwardly and downwardly between said casing and said flange on the receptacle; stop means 25 in said casing, for preventing turning movement of said receptacle by turning movement of said valve; a collar, encircling said axial conduit and both of said sleeves, exterior to said casing, whereby said receptacle may be axially adjusted 30 in said casing; and constricting means, in said collar, adjustable to frictionally secure said sleeves and receptacle in variable adjusted relation to said casing.

2. In means for separating particles of solid 35 material by flotation; the combination with a separator casing, which is conical, with its apex downward, and has a lateral inlet for the material to be separated, and lateral outlet for the material precipitated in said casing; of a conduit for flotation fluid extending axially in, and having vertically spaced lateral vents within, said casing; a circular receptacle for said fluid, surrounding said vents, in coaxial relation with said casing and conduit, and in radially spaced 40 relation with said casing; a flange at the top of said receptacle which is conical with its apex downward and in substantially equally spaced 45 relation with the inner wall of said casing from the bottom to the top of said flange; whereby upward movement of the flotation fluid in the space between said casing and flange is decelerated from bottom to the top of said flange and the lighter particles of solid material thereby freed for separation and discharged through 50 said lateral outlet; a diaphragm within the lower part of said receptacle between said vents, and having a fluid outlet port therethrough leading to the region in which the material is precipitated; valve means, including a cylindrical sleeve slidably fitted around said conduit and extending exterior to said casing; and means on said sleeve, exterior to said casing, whereby it may be adjustable to variably determine the relative proportions of fluid injected 55 into said receptacle at different heights, in accordance with the nature and quantity of the solid material being separated.

3. A structure as in claim 2; wherein the axial conduit extends through both the top and 70 bottom of the separator casing; a single fluid pump connected to both the top and bottom of said conduit; separate valve means respectively controlling the supply of fluid from said pump to the upper and lower ends of said conduit; 75

whereby the relative volumes of fluid respectively discharged downwardly and upwardly in said casing, by said pump, may be variably predetermined, in accordance with the nature and quantity of the solid material being separated.

4. A structure as in claim 2; wherein the axial conduit extends through both the top and bottom of the casing, and the lateral vents in said conduit are vertically spaced both above and below the top of the receptacle; means for supplying fluid to both ends of said conduit; and means for separately controlling the supply of fluid to the respective ends of said conduit; whereby the relative proportions of fluid discharged downwardly and upwardly in said conduit may be variably predetermined in accordance with the nature and quantity of the solid material being separated.

5. In means for separating particles of solid material by flotation; the combination with a separator casing, which is conical, with its apex downward, and has a lateral inlet for the material to be separated, a lateral outlet for the material precipitated in said casing, and a lateral outlet for the material not precipitated in said casing; of a conduit for flotation fluid extending axially in and through both the top and bottom of said casing, and having vertically spaced lateral vents within said casing; two circular fluid receptacles in coaxial relation with,

and interposed between, said casing and conduit in spaced relation with both; respective diaphragms in each of said receptacles extending between vertically spaced vents from said conduit within the respective receptacles, and each having vertical ports therethrough; means exterior to said casing, respectively in coaxial and rigid relation with said receptacles, whereby said receptacles may be relatively vertically adjusted with respect to said conduit and the vents therein and a completely annular fluid passageway is formed between the adjacent ends of the respective receptacles and may be varied in effective area and the relative volumes of fluid discharged upwardly and downwardly in said casing may be variably predetermined in accordance with the nature and quantity of the solid material being separated.

6. A structure as in claim 1; wherein the receptacle is vertically adjustable in the casing and the stop means in said casing, for preventing turning movement of said receptacle by turning movement of said valve includes an element fixed in said casing in eccentric relation with said conduit and extending vertically in a bearing in the lower portion of said receptacle in vertical slidable relation therewith.

RUSSELL SCOTT ELLIS.
